UNITED STATES PATENT OFFICE.

ALEXANDER L. MACKINTOSH, OF DENVER, COLORADO, ASSIGNOR OF ONE-HALF TO
DAVID R. RIDDICK, OF RAWLINS, WYOMING.

EDUCATIONAL TOY.

1,349,776.

Specification of Letters Patent. Patented Aug. 17, 1920.

Application filed November 25, 1918. Serial No. 264,051.

To all whom it may concern:

Be it known that I, ALEXANDER L. MACKINTOSH, a citizen of the United States, residing at Denver, in the county of Denver 5 and State of Colorado, have invented certain new and useful Improvements in Educational Toys; and I do declare the following to be a full, clear, and exact description of the invention such as will enable others skilled in the art to which it appertains to 10 make and use the same.

My invention has for its principal object to provide a simply constructed and inexpensive toy which will be educational to 15 the children using the same, due to the fact that a number of blocks are employed having numbers or letters, or both thereon, to be slid down a number of chutes over corresponding letters or numbers on the bottoms of such chutes.

A further object is to provide for the compact folding of the device for shipment, and to require little space in stores when placed 20 on sale, as well as in the home.

With the foregoing objects in view, the invention resides in the novel features of construction and unique arrangements of parts hereinafter fully described and claimed, the descriptive matter being supplemented by the accompanying drawings 25 which form a part of this application.

Figure 1 is a perspective view of the device set up for use.

Fig. 2 discloses perspective view of opposite sides of the block holding tray and its supporting board.

Fig. 3 is a longitudinal section of the device in position for use.

Fig. 4 is a similar view showing the device folded.

Figs. 5 and 6 are transverse sections on the planes indicated by the lines 5—5 and 6—6 of Fig. 4.

Fig. 7 discloses perspective views of the 45 opposite sides of one of the blocks.

Fig. 8 illustrates in perspective the opposite sides of one of the strips of cardboard or the like placed in the bottoms of the chutes.

50 In the drawings above briefly described, the numeral 1 designates a rectangular base board having an upstanding flange 2 around its edge, 3 refers to an inclined board having a similar flange 4 around its edge, 5 55 designates a platform at the upper end of

the board 3 and provided with a flange 6, and 7 indicates a vertical board for supporting the platform 5.

The inclined board 3 rests on one end of board 1 against its flange 2 and the upper 30 end of said board 3 is detachably connected with the forward edge of the platform 5, while the rear edge of the latter is hinged at 8 to the supporting board 7 which rests upon the base board 1, at the end of the latter opposite the lower end of the board 3. A brace 9 is pivoted to the board 7 and at 10 is detachably connected with the board 5 so as to properly hold the two in right 35 angular relation for use as seen in Fig. 1.

Any suitable detachable connection may be employed between the boards 3 and 5, but I prefer to form tongues 11 on the front edge of the latter for reception in slots 12 in the flange 4 at the upper end of board 3.

The upper side of board 3 is provided with a plurality of longitudinal chutes divided by ribs 13 suitably formed on said board, and strips 14 of cardboard or the like are preferably placed in the bottoms 40 of the several chutes, one side of each strip 14 having letters of the alphabet thereon as indicated at 15 (see Figs. 1 and 8), while the other side of the strip is provided with figures as indicated at 16 in Fig. 8. All 45 letters of the alphabet are preferably used and twenty-six figures are also employed. In some instance, the cardboard strips 14 might be dispensed with, in which instance the letters or figures could be painted on 50 the bottoms of the chutes.

A plurality of blocks 17 are provided to be slid down the several chutes, one side of each block having a letter of the alphabet thereon as indicated at 18 (see Figs. 1 and 95 7) while the other side of the block is provided with a numeral 19 as disclosed most clearly in Fig. 7. The letters 18 run from A to Z and the numerals 19 from 1 to 26.

The blocks 17 are placed upon the platform board 5 and if desired the latter may be provided with a plurality of troughs for their reception, said troughs being formed between ribs 20 on said board. It is intended that the child or children using the device shall pick out a block from the platform displaying the same character (figure or number) as the lowermost character at the bottom of one of the chutes, and that such block shall then be slid down the chute 100 105 110

over the selected character. This operation may be repeated until all of the characters in one chute are covered, after which the other chutes may be used. By providing the reversible strips 14 and the blocks 17 with numerals on one side and letters of the alphabet on the other, the child may be taught the letters of the alphabet and then numerals from 1 to 26. The device is not only amusing but is highly educational since it teaches the child to recognize the letters and numerals at a glance.

When the device is not in use, it may be folded as shown in Fig. 5. In so folding the toy, the tongues 11 are withdrawn from the slots 12 and the brace bar 9 is disconnected from the platform 5, thus permitting said platform and its supporting board 7 to be swung upon the hinges 8 into alignment. These parts may then be placed in the box formed by the board 3 and its flange 4, and the base board 1 with its flange 2 then acts as a cover. The article is thus in extremely compact form for shipment, to be placed on sale or to occupy little space in the nursery or home. Since probably the best results are obtained from the details shown and described, such details are preferably followed, but within the scope of the invention as claimed, considerable latitude is allowed for making such changes as occasion may dictate.

I claim:

1. An educational toy comprising a chute having educational characters on its bottom, and a plurality of blocks adapted to be slid along said chute, said blocks displaying characters corresponding to those aforesaid.
2. An educational toy comprising a chute, a reversible strip disposed in the bottom of said chute and bearing different educational characters on its opposite sides, and a plurality of blocks adapted to be slid along said chute over said characters, the opposite sides of said blocks bearing characters corresponding to those aforesaid.
3. A structure as specified in claim 1,

the upper end of said chute having a flange provided with a slot, a platform to support the blocks prior to their use, said platform having a tongue removably received in said slot, and a support movably connected to said platform.

4. An educational toy comprising a base board provided at its edge with an upstanding flange, an inclined board having a plurality of chutes on its upper side and equipped along its edge with an upwardly extending flange, the bottoms of said chutes displaying educational characters, a platform connected detachably with the upper end of said inclined board, a plurality of blocks supported normally on said platform and displaying educational characters corresponding to those aforesaid, said blocks being adapted to be slid down said chutes, a vertical board hinged at its upper end to the rear edge of said platform, the lower end of said supporting board resting on one end of said base board and the lower end of said inclined board resting on the other end thereof, said platform and supporting board being receivable within the flange of said inclined board when detached from the latter, said base board then forming a cover for the entire device.

5. An educational toy comprising an inclined board provided on its upper side with a plurality of chutes having educational characters on their bottoms, a plurality of blocks adapted to be slid down said chutes and bearing characters corresponding to those aforesaid, a horizontal platform extending from the upper end of said inclined board and adapted to normally support said blocks, and a leg member depending from said platform, said leg member and the lower end of said inclined board being adapted to rest on a horizontal surface to support the entire device.

In testimony whereof I have hereunto set my hand.

ALEXANDER L. MACKINTOSH.
